US00D804830S

(12) **United States Design Patent** (10) **Patent No.:** **US D804,830 S**
(45) **Date of Patent:** **** Dec. 12, 2017**

(54) **TEXTILE SHEET WITH A CAMOUFLAGE PATTERN**

(71) Applicant: **NTA Enterprise, Inc.**, Pittsburgh, PA (US)

(72) Inventor: **Michael A Rosswog**, Pittsburgh, PA (US)

(73) Assignee: **NTA ENTERPRISES**, Pittsburgh, PA (US)

(**) Term: **15 Years**

(21) Appl. No.: **29/569,740**

(22) Filed: **Jun. 30, 2016**

(51) LOC (10) Cl. **05-05**

(52) U.S. Cl.

USPC **D5/62**

(58) **Field of Classification Search**

USPC ... D5/6, 7, 8, 16, 25, 32, 37, 39, 43, 47, 53, D5/56, 57, 60, 61, 62, 66, 99, 59, 45, 26, D5/30, 35, 63, 3; D19/1, 5; D20/27, 28; D25/138, 150, 151, 156

(57) **CLAIM**

The ornamental design for a textile sheet with a camouflage pattern, as shown and described.

DESCRIPTION

The sole FIGURE is a top plan view of a textile sheet with a camouflage pattern according to the present invention. The broken lines surrounding the textile sheet with a camouflage pattern represent the boundaries to the claim and form no part thereof. The textile sheet with a camouflage pattern is flat and planar.

1 Claim, 1 Drawing Sheet
